UNITED STATES PATENT OFFICE.

BUNPACHI IITSUKA, OF ESCONDIDO, CALIFORNIA.

BUTTER-SLICING DEVICE.

1,073,761.

Specification of Letters Patent.

Patented Sept. 23, 1913.

Application filed May 26, 1913. Serial No. 769,973.

To all whom it may concern:

Be it known that I, BUNPACHI IITSUKA, a subject of the Emperor of Japan, residing at Escondido, in the county of San Diego 5 and State of California, have invented certain new and useful Improvements in Butter-Slicing Devices, of which the following is a specification.

This invention relates to butter slicing or 10 cutting devices and has for its object the provision of a device of this character adapted for use in cutting the usual pound prints of butter into the smaller rectangular pieces ordinarily served in hotels, restaurants, 15 lunch-rooms, and the like.

It is a further object of the invention to provide a structure of this character which may be very rapidly operated and one in which the size of the pieces into which the 20 butter is cut, may be varied at will.

Further objects and advantages of the invention will be set forth in the detailed description which now follows.

In the accompanying drawing, Figure 1 25 is a plan view of a butter cutter or slicer constructed in accordance with the invention, Fig. 2 is a side elevation thereof, and Fig. 3 is a front elevation thereof.

Like numerals designate corresponding 30 parts in all of the figures of the drawing.

Referring to the drawing, it will be seen that the body 5 comprises the bottom wall 6 and the side walls 7. The bottom wall 6 has a longitudinally extending slot 8 formed 35 therein through which the shank 9 of a headed member 10 passes, the head of said member lying on the under-side of the bottom wall 6 and said headed member being carried by a slot 11 which is upturned at 40 its forward end 12 and attached to a follower plate 13. Detachably secured to the slide 11 is a ratchet bar 14. The reason for detachably securing the ratchet bar to the slide is to render it possible to substitute one of these bars for another, the spacing of the teeth upon said ratchet bars varying, whereby the size of the slices into which the butter is cut, may be varied at will. 45 Journalized at 15 in the side walls 7, is a shaft carrying an offset crank 16. This crank has pivotally mounted thereon a pawl plate 17, the edge 18 of which engages the teeth of the ratchet bar 14. The convolutions of a coiled spring 19 embrace shaft 50 55 and one end of said spring is engaged with the body 5 at 20 and the opposite end

of said spring engages at 21 beneath an operating arm 22 that is carried by the shaft 15. It will therefore be seen that this operating handle is held in a normally elevated position by the action of said spring and that when the spring acts to throw this handle to its elevated position after the handle has been depressed, the crank 16 will have imparted thereto, a downward 60 and forward movement which will act through the pawl plate engaging the teeth of the ratchet bar, to impart a feeding movement to said ratchet bar toward the right in Fig. 1.

It will be understood that the butter to be cut is disposed in front of the follower plate 13 and that when this follower plate is moved toward the right, the butter will be projected through the front of the body 5 70 to a corresponding extent. To sever the butter longitudinally, a wire or other cutting element 23 is disposed vertically at the front end of the body. This wire extends between the bottom 6 and the flange 24 of a bridging element 25, said bridging element extending between and being secured to the side walls 7.

For severing the butter transversely, a transversely extending wire 26 extends between and is secured to the free ends of a yoke 27. This yoke is pivotally connected to and is supported by a yoke extension 28 of the operating arm 22, said pivotal connection being indicated at 29. A spring 30 80 extends between and is connected to the cross bars 27' and 28' of the yokes 27 and 28 and the function of this spring is to pull the top of the yoke 27 toward the cross bar 28' and to thereby hold the lower and free 85 ends of this yoke into engagement with guides 31 carried by the side walls. The reason for providing this structure is that while it is desired to have the wire 26 moved by the arm 22, it is necessary that this wire 90 move in a straight line, while the forward end of the arm 22 moves in the arc of a circle. By providing the guides 31 and pivoting the yoke 27 to the yoke 28 and connecting these two elements by the spring 95 30, the necessary straight line movement of the wire 26 is secured while still permitting the actuation of this wire by the arm 22. A guide strap 32 embraces the arm 22 and is carried by one of the side walls 7.

The method that I preferably employ for detachably securing the ratchet bar 14 to the

slide 11 is to notch the ends of this bar as at 33 and 34, the notch 33 engaging a screw or other headed member 35 carried by the slide and the notch 34 engaging the shank of a turn button 36. Various means of securing 5 this ratchet bar to the slide may be resorted to.

While the elements shown and described are well adapted to serve the purposes for 10 which they are intended, it is to be understood that the invention is not limited to the precise construction set forth, but includes within its purview such changes as may be made within the scope of the appended 15 claims.

Having described my invention, what I claim is:

1. In a device of the character described, the combination with a body portion comprising a bottom and sides and having an open front end, of an operating handle pivoted thereto, a follower, a pawl and ratchet connection between said follower and said operating handle, a yoke pivoted to said operating handle, a cutting wire carried by said yoke and traveling vertically across the open front end of the body, and a spring 20 connected to said yoke and to a portion of said operating handle for drawing said wire toward the front end of the body portion. 25

2. In a device of the character described, the combination with a body portion having an open front end, of a swinging operating handle pivoted in the side walls of said body 30 portion, a yoke pivoted to said operating handle, a cutting wire carried by said yoke and extending transversely of the body portion, guides carried by the body portion, and a spring extending between said yoke and a portion of the operating handle for drawing 35 the lower portion of said yoke into engagement with said guides, said yoke being bodily movable with the operating handle whereby said cutting wire is caused to travel in a vertical straight line while the operating handle by which it is carried travels in the arc of a circle. 40

3. In a device of the character described, the combination with a body portion having 45 an open front end, of a swinging operating handle pivoted in the side walls of said body portion, a yoke pivoted to said operating handle, a cutting wire carried by said yoke and extending transversely of the body portion, guides carried by the body portion, a spring extending between said yoke and a portion of the operating handle for drawing 50 the lower portion of said yoke into engagement with said guides, said yoke being bodily movable with the operating handle whereby said cutting wire is caused to travel in a vertical straight line while the operating handle by which it is carried travels in the arc of a circle, and a spring normally 55 tending to elevate said operating handle. 60

4. In a device of the character described, the combination with a body portion comprising a bottom and sides and having an open front end, of an operating handle pivoted thereto, a follower, a pawl and ratchet connection between said follower and said operating handle, a yoke pivoted to said operating handle, a cutting wire carried by said yoke and traveling vertically across the open front end of the body, a spring 70 connected to said yoke and to a portion of said operating handle for drawing said wire toward the front end of the body portion, and a spring normally holding said operating handle in an elevated position. 80

5. In a device of the character described, the combination with a body portion, of a slide mounted therein, a follower carried by said slide, a ratchet bar removably mounted upon said slide, an operating handle, an offset crank carried by said operating handle, and a pawl plate carried by said crank and engaging said ratchet bar. 85

6. In a device of the character described, the combination with a body portion, of a slide mounted therein, a follower carried by said slide, a ratchet bar removably mounted upon said slide, an operating handle, an offset crank carried by said operating handle, a pawl plate carried by said crank and engaging said ratchet bar, and spring means 90 serving to normally hold said operating handle in an elevated position. 95

7. In a device of the character described, the combination with a body portion, of a slide mounted therein, a follower carried by said slide, a ratchet bar removably mounted upon said slide, an operating handle, an offset crank carried by said operating handle, a pawl plate carried by said crank and engaging said ratchet bar, and a cutting element 100 carried by said operating handle. 105

8. In a device of the character described, the combination with a body portion, of a slide mounted therein, a follower carried by said slide, a ratchet bar removably mounted upon said slide, an operating handle, an offset crank carried by said operating handle, a pawl plate carried by said crank and engaging said ratchet bar, spring 110 means serving to normally hold said operating handle in an elevated position, and a cutting element carried by the operating handle. 115

9. In a device of the character described, the combination with a body portion having an open front end, a cutting wire extending vertically across said open front end and fixed thereto, a horizontally extending wire disposed across said open front end, a yoke 120 of inverted U-form between the terminal ends of which said latter wire extends and by which said wire is carried, an operating handle having pivotal mounting within the walls of said body portion adjacent the rear 125 130

end of said body portion and having its front end bent to yoke formation and embracing the first named yoke, means for pivotally mounting the first named yoke within the yoke formed by the front end of the operating handle, and a spring extending between said yokes as and for the purposes set forth.

10. In a device of the character described, the combination with a body portion having an open front end, a cutting wire extending vertically across said open front end and fixed thereto, a horizontally extending wire disposed across said open front end, a yoke 15 of inverted U-form between the terminal ends of which said latter wire extends and by which said wire is carried, an operating handle having pivotal mounting within the walls of said body portion adjacent the rear 20 end of said body portion and having its front end bent to yoke formation and embracing the first named yoke, means for pivotally mounting the first named yoke within the yoke formed by the front end of the operating handle, a spring extending between 25 said yokes, and vertically extending guides disposed upon the outer faces of the vertical ends of the side walls of the body portion and against which the lower end of 30 the yoke of inverted U-shape travels.

11. In a device of the character described,

the combination with a body portion having an open front end and having a longitudinally extending slot formed in its bottom, of a slide resting upon said bottom, a headed member extending through said slide and engaging beneath the bottom, said headed member being carried by said slide, a ratchet bar having its opposite ends notched, a fixed member carried by the slot with 35 which one of said notched ends engages and a movable member carried by the slide and adapted to engage the other of said notched ends, whereby said ratchet bar is removably held in engagement with said slide, an operating handle having a pivotal mounting in the side walls of the body portion and comprising an offset crank lying between said side walls, a ratchet plate pivotally mounted upon said crank, a spring, one end 40 of which engages said body portion and the other end of which engages said handle to normally throw said handle to an elevated position, and a cutting element carried by the free end of said operating handle, substantially as shown and described. 45

In testimony whereof I affix my signature in presence of two witnesses.

BUNPACHI IITSUKA.
